COUNTERFEIT MONEY DETECTOR

John H. Ruth, Brooklyn, N. Y.

Application January 5, 1939, Serial No. 249,415

3 Claims. (Cl. 88—14)

This invention relates to devices for detecting counterfeit money.

One object of the invention is to provide a device for detecting counterfeit money by improved means affording direct magnified comparison with known genuine money.

Another object of the invention is to furnish an improved device of the character described of relatively inexpensive, simple, and compact construction whereby bills of different denominations can be rapidly compared with known genuine bills without causing eye strain and without requiring that too much dependence be placed on the judgment or reliability of the observer.

Heretofore it has been known to examine money by carefully noting the threads or colored strands therein, in order to detect spurious bills. This method depended solely on the fact that paper money is laminated, with fine colored strands incorporated in or between the laminations. Counterfeit bills were known to have delicate colored ink marks to simulate the colored strands referred to. Hence the observer required experience and had to examine the bills very closely, generally with the unaided eye so that a spurious bill would often escape detection.

The present invention aims to provide a device which is adapted for universal use by retailers, supply houses and other commercial concerns, as well as by banks. It aims to relieve the observer of the strain previously imposed on him by providing a novel method of comparison of the money submitted, with known genuine bills, by reference to the printing on the bills so that the finest lines, dots and spaces or breaks can be noted at a glance. This method is inherently more suited to the ordinary observer than the method of studying the colored strands, because the eye is accustomed to making comparisons, and its accuracy in this regard is easily developed. However, should the observer so desire, he may also use my device for a magnified inspection of the colored strands or texture of the paper particularly at the points bearing the numerals denoting the amount of the bill, because frequently these numerals are changed on an otherwise genuine bill.

It is therefore a further object of the invention to provide an improved device for accomplishing the method and the advantages above referred to.

Other objects and advantages of the invention will become apparent as the specification proceeds.

With the aforesaid objects in view, the inven-

tion consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a vertical sectional view on the line 1—1 of Fig. 2, showing a device embodying 10 the invention.

Fig. 2 is a plan view of the device.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail, 10 denotes a device for detecting counterfeit paper money, embodying the invention; and it will be understood that this device is also adapted to detect counterfeit signatures and the like, as will be evident. This device includes a casing 11 which is longitudinally vertically split at 12 to provide a plurality of separate casing sections 13 and 14. These may be suitably interconnected as by bolts 15 to provide a rigid structure. As thus arranged, the casing 11 affords a top chamber 16 defined by front and rear walls 17, 18 respectively, side walls 19, 20 respectively, and a forwardly downwardly sloping top wall 21. The lower part of the casing 11 may be considered as providing a base 22, adapted to be closed by a plate 23 which may be removably secured thereto by screws, or which may removably snap into the rabbet 24 marginally formed in the base. The forward part of the latter may project frontward as at 25, so that a table or other support 26 may lead inward therefrom, in parallel relation to the top wall 21. Formed in the side walls 19, 20, along the plane of the table 26, are slots 27 which extend inward from a transverse entrance slot 28 in the front wall 17, up to a point 29 at which the slots 27 terminate in tapered form to releasably clamp or snugly engage a bill, as hereinafter more fully described. It will now be perceived that by splitting the casing 11, as well as the table 26, along the plane at 12, a very simple structure is afforded, which is adapted to be eas-

ily molded, and which, except for the plate 23, may consist of only two parts, namely, the casing sections 13, 14. It will be appreciated that the casing 11 may be made of any other size, shape, structure or arrangement.

Journalized in the walls 19, 20 is a shaft 30 carrying a turntable or polygonal rotor 31 affixed thereto, having any number of faces, but being desirably in the form of an equilateral triangle in cross section, so that bills in 5, 10 and 20 dollar denominations may be easily angularly applied to said faces as hereinafter described. Affixed to the shaft 30 externally of the casing 11 is a polygonal indicator 32, in this case triangular, and bearing numerals at 33 corresponding to the denominations of the bills on the turntable 31, it being understood that the faces of the latter and of the indicator are aligned to correspond with each other. A head 34 may be affixed to the indicator or to the shaft 30 for causing rotation. To set the device against accidental movement, the indicator 32 may have on its inner face a rigid tit or projection 35 located adjacent to a corner of the triangle, and adapted to engage in any one of three recesses 36 formed in the outer face of the side wall 19, to hold the turntable in any one of its three operative positions. For a resilient snap engagement of the tit 35 in the recesses 36, an expansion coil spring 37 may extend around the shaft 30 and bear against the side wall 19 and an end of the turntable to thus actuate the longitudinally movable shaft 30 to pull the indicator 32 against the wall 19, whereby the engagement at 35, 36 will operate releasably in a well known manner. If desired, longitudinal movement of the shaft 30 may be limited in any well known manner.

Formed in the top wall 21 of the casing 11 is an opening 38 provided in the mating casing sections 13, 14, said opening affording an annular seat for a magnifying accurately ground and highly polished lens 39 that may be suitably secured as by a bezel 40. This achromatic objective lens is of sufficiently large diameter to embrace in its field the upper face of the turn table 31 and a substantial area of the fixed table 26, and yet to afford relatively high magnification at a small focal distance, whereby the device 10 may be kept small and compact.

50 A source of light, such as an electric lamp 41 may have its base 42 mounted on a support which may include bracket arms 43 formed for this purpose on the individual casing sections 13, 14. The lamp may be located along the center plane of the casing 11, and a reflector 44 therefore may extend the full width of the casing 11 and may be suitably affixed to the rear wall 18. The arrangement is such that the lamp and reflector are adapted to project light with substantially equal intensity upon the upper face of the turntable 31 and upon the fixed table 26, and yet to lie rearward out of the field of vision of the lens 39.

If desired, a switching device may be provided for automatically causing the lamp 41 to light when a bill such as 45 is inserted for comparison, and to cause the lamp to be deenergized when the bill is withdrawn. For a reason hereinafter indicated, the bill is longitudinally folded adjacent to one edge, as at 46, and this fold which is of greater stiffness than the rest of the bill, may be utilized to cause counterclockwise swinging motion of a bell crank lever 47, about its pin or shaft 48 that is affixed to the side wall 19. A

light, tension coil spring 49 is affixed at 50 to the side wall 19 and is connected to the lever 47 to move the latter clockwise. The other arm 51 of the bell crank lever is adapted to engage a spring contact 52 affixed to the side wall 19. The circuit to the lamp may include a lead 53 entering the casing 11 through a hole, with one wire 54 of the lead being directly connected to the lamp base, and the other wire 55 being connected to the bell crank lever preferably adjacent to its axis. A wire 56 may connect the contact 52 with the lamp base. By arranging the bell crank lever and its switch adjacent to a side wall of the casing, there is no obstruction in applying bills to the faces of the turntable 31. Since the fixed table 26 may end short of the ends of the slots 27, this table may act as a stop to limit movement of the lever 47 under tension of the spring 49.

I have found that it is desirable in detecting counterfeit money to make the comparison principally with the head or picture of a person that is always carried by paper money. Hence I arrange the bills that are to be mounted on the turntable 31 by folding each bill several times, into small, compact and thin form so as to leave the head fully exposed. It is naturally desirable to maintain the bills intact and also to permit their easy removal at night when the place of business is closed. Hence I provide channel elements 57 extending along the ends of each face of the turntable, each element being closed at one end to form a stop, for which reason these elements may be of U-shaped form, so that there is a longitudinally extending channel element 58 on each face of the turntable. It will now be seen that the folded genuine bills above described, denoted by the numerals 59, may be slid in place to be each marginally held down on three edges by the channel elements referred to. By providing a turntable of triangular form, each of these folded bills can be easily inserted and removed at a large obtuse angle when the device 10 is inverted and the plate 23 removed.

It will be noted that the arrangement is such that the fold edge 46 of the bill 45 comes directly against an adjacent edge of any one of the bills 59, to obtain maximum proximity, and that the tapered slot portions at 29 not only form stops for the bill 45 but snugly hold the same down on the table 26. In order that the exposed faces of the bills 45, 59 lie in a single plane for accurate comparison through the lens 39, the turntable 31 may be of such size as to allow for the thickness of the folded bills 59. It will be understood that the fold 46 in the bill 45 is so located that the heads on the bills 45 and 59 are in direct juxtaposition.

Since each denomination of paper money carries its individual head, the observer is bound to note a bill whose amount has been raised.

The manner of using the device 10 will now be described. The operator folds known genuine bills as described and applies them to the turntable faces to correspond with the numerals at 33. He then secures the plate 23 in position and the device 10 is ready for use. A bill that is submitted is longitudinally folded as hereinbefore described, and is inserted in the slots 27 as far as it will go. Thus the bell crank lever 47 is operated to close the circuit to the lamp 41. Now the operator looks through the lens 39 and instantly detects the slightest discrepancies. If inspection of any other part of the bill 45 is desired, the same may be slid transversely of the table and viewed through the lens 39, while the

lamp is lit. The device 10 may be made so small, that it can be mounted on a cash register so as to be unnoticed by a customer. It may be made larger for banks, and may be arranged for inspection of a larger portion of the bill as desired.

5 I claim:

1. A device for detecting counterfeit bills, including a casing providing a chamber, a polygonal turntable rotatable about its horizontal axis and presenting on its different faces comparison indicia for bills of different denominations, the casing having means for supporting a bill in the chamber including slots along a plane that coincides with the plane of an upper face 10 of the turntable, said slots extending along the front and side walls of the casing for the insertion of a bill whose ends project outside of said chamber, means for rotating the turntable, a source of light in the casing, and a magnifying lens on the casing embracing in its field of vision the upper face of the turntable and a portion of the chamber adjacent thereto for a direct comparison of the bill with said indicia, a polygonal head outside of the casing being connected to the turntable, the faces of said head being alined with those of the turntable, and indicia on the faces of the head corresponding to the indicia on the faces of the turntable.

15 2. A device for detecting counterfeit bills, including a casing providing a chamber, a polygonal turntable rotatable about its horizontal axis and presenting on its different faces comparison indicia for bills of different denominations, the casing having means for supporting a bill in the chamber including slots along a plane that coincides with the plane of an upper face of 20 the turntable, said slots extending along the front and side walls of the casing for the insertion of a bill whose ends project outside of said chamber, means for rotating the turntable, a source of light in the casing, and a magnifying lens on the casing embracing in its field of vision the upper face of the turntable and a portion of the chamber adjacent thereto for a direct comparison of the bill with said indicia, the slots in the side walls having tapered end portions for 25 snugly clampingly engaging a bill inserted thereinto.

25 3. A device for detecting counterfeit money, including a casing providing a chamber, a turntable in said chamber for mounting different comparison indicia, said chamber having a slot opening for insertion of a bill, means within said chamber for mounting the bill inserted in said slot, a source of light in the chamber for illuminating the turntable and said bill mounting means, and a single magnifying lens mounted on a wall of the chamber and embracing within its field of vision the turntable and a portion of the bill mounting means for direct magnified comparison of the bill with said indicia, the bill mounting means including a table integral with the casing, the latter being longitudinally vertically split through the lens opening and the table 30 and providing two casing sections, each having a portion of the slot opening, and means for connecting together said casing sections.

JOHN H. RUTH.

the turntable, said slots extending along the front and side walls of the casing for the insertion of a bill whose ends project outside of said chamber, means for rotating the turntable, a source of light in the casing, and a magnifying lens on the 5 casing embracing in its field of vision the upper face of the turntable and a portion of the chamber adjacent thereto for a direct comparison of the bill with said indicia, a polygonal head outside of the casing being connected to the turntable, the faces of said head being alined with those of the turntable, and indicia on the faces of the head corresponding to the indicia on the faces of the turntable.

10 15 20 25 30

the turntable, said slots extending along the front and side walls of the casing for the insertion of a bill whose ends project outside of said chamber, means for rotating the turntable, a source of light in the casing, and a magnifying lens on the casing embracing in its field of vision the upper face of the turntable and a portion of the chamber adjacent thereto for a direct comparison of the bill with said indicia, a polygonal head outside of the casing being connected to the turntable, the faces of said head being alined with those of the turntable, and indicia on the faces of the head corresponding to the indicia on the faces of the turntable.
